UNITED STATES PATENT OFFICE.

MARGARET D. MACKINNON, OF LINCOLN, NEBRASKA, ASSIGNOR TO MARSHALL FIELD & COMPANY, OF CHICAGO, ILLINOIS, A CORPORATION OF ILLINOIS.

DESIGN FOR A COMBINATION CHILD'S SUIT.

Application filed January 31, 1925. Serial No. 12,213. Term of patent 14 years.

To all whom it may concern:

Be it known that I, MARGARET D. MACKINNON, a citizen of the United States, residing at Lincoln, in the county of Lancaster and State of Nebraska, have invented a new, original, and ornamental Design for a Combination Child's Suit, of which the following is a specification, reference being had to the drawings forming part thereof.

In the drawings,

I claim:

The ornamental design for a combination child's suit, as shown.

MARGARET D. MACKINNON.
